ARMATURE BRAKE

Ralph A. Nevinger, Greenville, Ill.

Application February 2, 1938, Serial No. 188,390

3 Claims. (Cl. 172—36)

This invention relates to clocks of the electrical type, and more particularly to clocks or time pieces designed for use where they must be frequently started and stopped, as is the clock forming a part of the score board mechanism disclosed in my pending application filed July 2, 1935, Serial Number 29,560.

The primary object of the invention is to provide a stop or brake adapted to operate to immediately stop the hands of the clock when the circuit to the clock motor has been broken.

Another important object of the invention is to provide a device of this character which may be readily and easily mounted on a clock frame of known construction, eliminating the necessity of providing auxiliary means or circuits for operating the braking means.

Still another object of the invention is to provide a braking mechanism which will operate directly on the armature of the motor, the construction of the brake being such as to include few parts, to the end that the cost of the upkeep of the mechanism will be exceptionally low.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawing: Figure 1 is a rear elevational view of an electric clock, equipped with a braking device constructed in accordance with the invention.

Figure 2 is a side elevational view thereof.

Figure 3 is a sectional view through the armature and braking device operating in conjunction therewith.

Referring to the drawing in detail, the reference character 5 designates the casing of the usual electric clock, and as shown, the clock mechanism includes a frame indicated generally by the reference character 6, which is secured to the rear surface of the casing 5, by means of the bolts 7.

The frame 6 provides a support for the field coils 8 and armature 9 of the clock motor.

Secured to the frame 6, is an arm 10, which is formed with an opening to accommodate the shaft 12 on which the arm 13 is pivotally mounted, the shaft 10 being provided with nuts 11, securing the shaft in position. A sleeve indicated

by the reference character 11' is secured to the arm 13 and is positioned over the shaft, providing a bearing for the arm 13. This arm 13 is formed with a lower offset portion which is supplied with strips of metal 17 sensitive to the action of electric current passing through the field coils 8, so that when electric current passes through the field coils, the lower end of the arm 13 will be attracted. These strips of metal also provide means for weighting the arm, to normally hold the arm in a position as shown by Figure 3 of the drawing.

Extending through a threaded opening in the arm 13, is a screw 15, which is held within the opening, against movement, by means of the lock nut 16. This screw 15 is of a length to extend into the casing in which the armature of the motor operates, contacting with the armature, as shown by Figure 3 of the drawing. Under normal conditions, that is when electric current is not passing through the field coils 8 of the electric motor, the pivoted arm 13 will move to cause the screw 15 to contact the armature, preventing rotary movement thereof.

When the electric circuit to the motor is completed, the electric current passing through the field coils of the motor, will attract the lower end of the pivoted arms 13, moving the screw 15 out of contact with the armature, and permitting the armature to rotate freely. It follows that when the electric current has been cut off, the arm 13 will move the screw 15 into engagement with the armature, stopping movement thereof instantaneously with the stopping of the motor.

From the foregoing it will be seen that due to the construction shown and described, the motor which is controlled from a point remote from the clock mechanism, will also operate to control the braking mechanism, without the necessity of employing additional wiring, switches or the like, the action of the brake being simultaneous with the stopping and starting of the clock motor.

Having thus described the invention, what is claimed is:

1. The combination with the field coils and armature of the motor of an electrical device, of a magnetic brake comprising a pivoted member normally contacting with the armature, restricting rotary movement of the armature, and said pivoted member adapted to be attracted by the field coils of the electrical device when energized, moving the pivoted member out of engagement with the armature.
2. The combination with the field coils and

armature of an electrical motor, of a magnetic brake comprising a pivoted arm, a weight on one end of the arm and disposed adjacent to a field coil of the motor, the weighted end of the arm being responsive to the action of electric current passing through the field coils, a member at the opposite end of the pivoted arm and adapted to engage the armature of the motor, restricting movement of the armature when the electric current to the motor is broken.

3. The combination with the field coils and

armature of the motor of an electrical device, of a magnetic brake including a pivoted arm, a screw extending through one end of the arm and normally resting against the armature, restricting movement of the armature, the opposite end of the arm being disposed adjacent to one of the field coils, one end of the arm adapted to be attracted by the field coils when energized, moving the screw out of engagement with the armature and releasing the armature. 5

RALPH A. NEVINGER.
